Patented May 14, 1963

195,214

PORTABLE SERVING TABLE OR SIMILAR ARTICLE

Clifford L. Rowse, 319—9 Dallas St., Houston, Tex.

Filed Oct. 4, 1961, Ser. No. 66,967

Term of patent 14 years

(Cl. D33—14)

Fig. 1

Fig. 2

FIGURE 1 is a side elevational view of a portable serving table or similar article showing my design;

FIGURE 4 is a top perspective view on an enlarged scale with the front leaf foreshortened and with the top shelf pivoted to an alternate position.

I claim:

The ornamental design for a portable serving table or similar article, substantially as shown.
